(57) CLAIM

We claim the ornamental design for a packing box for refrigerator, as shown and described.

DESCRIPTION

FIG. 1 is a front/right-side/top perspective view of a packing box for refrigerator showing our new design;
FIG. 2 is a front-side elevational view thereof;
FIG. 3 is a rear-side elevational view thereof;
FIG. 4 is a left-side elevational view thereof;
FIG. 5 is a right-side elevational view thereof;
FIG. 6 is a top-side elevational view thereof;
FIG. 7 is a bottom-side elevational view thereof.

FIG. 8 is a front perspective view of the design shown partially collapsed; and,

FIG. 9 is a front perspective view of the design shown fully collapsed.

The top and bottom portions of the packing box have been removed in FIGS. 8 and 9 for convenience of illustration.
